STRIP FEEDING DEVICE

Albert W. Metzner, Dayton, Ohio, assignor to The Standard Register Company, Dayton, Ohio, a corporation of Ohio

Application July 26, 1950, Serial No. 175,962

24 Claims. (Cl. 282—21)

1

This invention relates to feed devices, and more particularly to the kind used to advance continuous strips of series connected marginally punched record forms. Although not so limited, the invention has particular application to autographic registers and like machines, wherein marginally perforated record forms are advanced successively to and from a recording position upon a writing table.

A general object of the invention is to produce a new pin feed device for use in strip feed mechanisms which offers the advantage of being smaller in size and requiring less working area than prior devices while operating with equal efficiency and with less likelihood of damage to the strip or feed device.

Another object of the invention is to present a generally new pin type feed device in which the pins are always perpendicular to the strip.

With special reference to autographic registers, a further object of the invention is to increase the amount of useful writing space on each form.

Still another object of the invention is to embody the feed devices in a unitary assembly carried by the writing table.

A still further object of the invention is to allow a pair of parallel feed devices to be adjusted toward and away from one another to compensate for variations in the distance between marginal strip perforations.

Still another object of the invention is to provide a simplified operating mechanism for the pin feed devices, including means for positively limiting and defining the cyclic movements of such mechanism.

A further object of the invention is to provide a strip feeding device possessing the advantageous structural features, the inherent meritorious characteristics and the mode of operation herein mentioned.

With the above primary and other incidental objects in view as will more fully appear in the specification, the invention intended to be protected by Letters Patent consists of the features of construction, the parts and combinations thereof, and the mode of operation, as herein-after described or illustrated in the accompanying drawings, or their equivalents.

Referring to the accompanying drawings, wherein is found the preferred but obviously not necessarily the only form of embodiment of the invention,

Fig. 1 is a view in side elevation of an autographic register in accordance with the instant invention;

2

Fig. 2 is a detail view of a latch mechanism for the operating controls, showing such mechanism in effective locked position;

Fig. 3 is a view similar to Fig. 2 showing the latch mechanism rendered ineffective;

Fig. 4 is a detail view in side elevation of a pin feed device utilizing three pins;

Fig. 5 is a view similar to Fig. 4, showing a four pin device;

Fig. 6 is a detail plan view of the unitary form advancement mechanism;

Fig. 7 is a view in exploded isometric of one end of the form advancement mechanism;

Fig. 8 is a view in perspective of the upper right hand corner of the register, disclosing the increased writing space available on the forms;

Fig. 9 is a detail view in perspective of an element in the operating controls; and

Fig. 10 is a view of an alternative form of pin feed device.

Like parts are indicated by similar characters of reference throughout the several views.

Referring to the drawings, the invention is disclosed in connection with an autographic register of a conventional kind, utilizing marginally punched record forms. The structure of the register includes, as shown in Fig. 1, a casing 11 overlaid at the top thereof by a writing table 12. The table 12 is hinged at the rear of the register to a casing supported bracket 13. A lid 14 for the register is pivotally connected to the front end of the casing 11.

The record forms, shown at 15 in Fig. 8, ordinarily comprise superposed continuous strips, made up of interconnected sets of forms and folded in the rear of the register, with the leading end of the strips extending upon the writing table 12. Marginal perforations 16 in the forms are engaged by pin feed devices (to be described) operated by a crank 17 (Figs. 1 and 6) to advance successive sets of forms to and from a recording position upon the writing table.

In accordance with the instant invention, the form advancement mechanism is comprised in a unitary assembly carried by the writing table 12 on the underside thereof. As seen particularly in Figs. 1, 6 and 7, a support bar 18 extends transversely beneath the table 12 and is secured thereto by screws 19. At its right hand end (as viewed in Fig. 6) projecting studs 21 are set in the support 18 and slidably mount an auxiliary support 22 which is in effect a continuation of the support bar 18. An adjustment screw 23 passes through the auxiliary support 22, in threaded engagement therewith, and is held against axial motion in the end of support bar

18, the construction and arrangement providing for a lateral shifting of the auxiliary support 22 relative to the support bar 18 by manipulative adjustment of the screw 23.

The auxiliary support 22 mounts a pin feed device 24, including feed pins 25, the device 24 underlying a plate 26 (Fig. 8) which is secured to the support 22 by screws received in tapped openings 27 (Fig. 6) in the support. The plate 26 is accommodated in a cut out opening 28 (Fig. 8) in the edge of writing table 12 and is constructed and arranged to form a part of the table. A longitudinal slot 29 in the plate 26 permits passage of the feed pins 25 through the writing table in order that they may engage the perforations 16 in the forms 15. Lateral adjustment of the auxiliary support 22, such motion being transferred to the feed device 24 and the plate 26, enables accurate alignment of the feed pins with the perforations in the forms.

Adjacent to the opposite or left hand end of the support bar 18 is another feed device 31 substantially identical to the device 24 and having pins 32 to engage the opposite marginal edge of the forms through a slot in the writing table similar to slot 29. The feed devices 24 and 31 are rotated through operation of the crank 17. The crank is fastened to a stub shaft 33 journaled in a plate 34 bolted to a rearwardly extending arm 35 of the support bar 18. Mounted on the shaft 33 to rotate therewith is a gear 36 meshing with a pinion 37 on a shaft 38. The shaft 38 extends through a cut out opening 39 in the plate 34 and through the arm 35 to a journaled mounting in a vertical wall 41 of the support bar, the wall 41 being laterally spaced from the arm 35. Adjacent to the wall 41 a gear 42 is secured to the shaft 38 and meshes with a pinion 43 fast on a shaft 44. The shaft 44 is rotatably mounted at its one end in a projection 45 on the support bar 18 and similarly mounted at its opposite end in the auxiliary support 22, the shaft being a fabricated element incorporating an expansion joint 46 to allow the previously described relative lateral adjustment of the auxiliary support 22. The feed devices 24 and 31 are operatively associated with the opposite ends of the shaft 44, as will hereinafter more clearly appear. Accordingly, the turning of the crank 17 is effective, through the described driving connections, to operate the feed devices and advance the forms.

So that the extent of advancement of the forms may be positively defined, a latch mechanism is provided, including a stud 47 set in the gear 36 and a latch 48 having a cut out opening 49 to receive the stud. The latch 48 presents slots 51 and 52, the latter having an inclined lower edge, receiving fixed studs 53 in an end wall 54 of the support bar 18 spaced from the vertical wall 41 and connected thereto by a web 55. The latch 48 is accordingly slidable to and from a limiting position with respect to the stud, its motion being a combination sliding and tilting movement by reason of the slope of the slot 52. A spring 56, tensioned between a lateral pin 57 on latch 48 and an upright post 58 in web 55, urges the latch in a direction to engage opening 49 with stud 47. With the parts so engaged, the gear 36 cannot be turned and the crank 17 is accordingly latched against movement. Release of the latch 48 is accomplished by a finger 59 engaging an ear 60 on the upper edge of latch 48. The finger 59 is secured to a shaft 62 rotatably mounted in the end wall 54 and further mounting a finger manipulative lever 63. As shown in

Fig. 6, the lever 63 is arranged alongside the crank 17 so that it may be depressed to release latch 48 just prior to the turning of the crank, the two operations being performed at about the same time by the same hand of the operator. The initial motion of the crank moves the stud 47 out of cooperative relation with the latch opening 49 (see Fig. 3) so that the lever 63 may be promptly released, allowing the latch 48 to return to a position to intercept the stud 47 and so provide a limit stop for motion of the crank (see Fig. 2). In the illustrated instance there is but a single stud 47. Accordingly, the crank is free to make one complete turn. Should it be desired to limit the cyclic operation to some fractional part of a complete turn then additional studs may be installed on the gear 36, in a suitable relation to one another.

The gear train driving the pin feed devices is intended for operation in only one direction, that indicated by the arrows in Fig. 7. To inhibit motion in the opposite direction there is mounted on shaft 38 a roller 64. Bearing upon the roller 64 is a cam 65 eccentrically mounted on a stud 66 journaled in the supporting arm 35. That part of the edge of cam 65 which engages the roller 64 is serrated for better gripping engagement. The rotation of the roller 64 is unopposed by cam 65 during rotation of the shaft 38 in a clockwise direction, as seen in Fig. 7. Should the shaft be turned in the opposite direction, however, the high part of the cam is brought to bear on the roller which is accordingly prevented from rotating. A spring detent 67 holds the cam 65 in cooperative relation with the roller 64.

The support bar 18 also provides a mounting for the tear bar 68 which rests on the writing table and holds the forms thereon. The bar 68 is carried between arms 69 secured to opposite ends 40 of a shaft 71 journaled between respective projections on the support bar 18 and the auxiliary support 22. The tear bar assembly is urged downward by tension springs 72 anchored to suitable points on the principal and auxiliary supports. A coil spring 73 on the shaft 71 bears on the auxiliary support 22 to maintain a pressure on the threads of the adjustment screw 23.

Considering now the pin feed devices 24 and 31, since both are the same in construction and mode of operation a description of the device 31 will suffice for both. The pins 32 thereof are essentially cylindrical in shape with a square base 74 and an offset base extension 75. A pivot stud 76 protrudes laterally from each base portion 74 while a pivot stud 77 protrudes laterally from the base extension 75, the respective studs being vertically aligned with one another in the longitudinal axis of the pins.

The studs 76 and 77 extend in opposite directions from the pins 32 and are respectively received in longitudinal openings in discs 78 and 79. The disc 78 is secured to the end of shaft 44 while disc 79 is formed with a central stub shaft 81 rotatably received in an opening 82 in the fixed support arm 35. As shown more clearly in Fig. 4, the disc 79 is eccentrically mounted with respect to the disc 78, the studs 76 and 77 engaging the disc at corresponding points adjacent the peripheries thereof. In the illustrated instance there are three pins 32 although this number may be increased or reduced, as suggested in Fig. 5 where a pair of discs 83 and 84 mount four pins 32.

The construction and arrangement of the feed device 31 accordingly is such as to present a series

of pins which, in response to rotation of the device as effected by operation of shaft 44, move in an upright position through a rotary path of relatively small radius. The pins occupy a perpendicular position relatively to the writing table 12 and the forms 15 and maintain such position as they enter in and are withdrawn from the perforations 16. Since the feed pins have relatively short longitudinal travel relatively to the writing table, a greater part of the forms is available to be written upon than in prior registers. Thus, as shown in Fig. 8, carbon paper 86 which is interleaved with the forms 15 can be brought up to the first perforation on a form or within less than one inch from the leading edge thereof.

In the device 31 it will be understood that the disc 78 is positively driven by the shaft 44 and that the disc 79 is driven through the pins 32. An alternative arrangement is possible as shown in Fig. 10, wherein a pair of discs 87 mount pins 88 in the same manner as device 31 but with the disc formed as gears and meshing with a drive gear 89 corresponding to the gear 42.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. In a strip feed mechanism, a pin feed device including a pair of rotatable discs arranged in spaced apart parallel relation, and feed pins carried between said discs and pivotally connected to both thereof at respectively different points axially of the pins, said pins interconnecting said discs for unison rotation thereof.

2. In a strip feed mechanism, a pin feed device including a rotatable disc, feed pins pivotally mounted on one side of said disc at spaced apart points adjacent the periphery thereof to revolve about the axis of said disc in response to rotation of the disc, and means for maintaining said pins in an approximately upright position during rotation of said disc.

3. In a strip feed mechanism, a pin feed device, including a rotatable carrier, feed pins pivotally mounted on said carrier, and a rotatable guide member in offset parallel relation to said carrier and pivotally connected to said pins to maintain the pins in an upright position during rotation of said carrier.

4. In a strip feed mechanism, a pin feed device, including a rotatable carrier, feed pins pivotally mounted on said carrier, said pins being connected to said carrier intermediate their respective ends, and guide means eccentrically disposed with respect to the axis of said carrier and engageable with said pins adjacent their one ends to maintain the pins in an upright position during rotation of said carrier.

5. In a strip feed mechanism, a pin feed device, including one or more pins, a pair of pivot

supports for each pin spaced apart in the longitudinal axis of said pin, and separate carriers for said pivot supports rotatable about respectively offset centers.

5 6. In a strip feed mechanism, a pin feed device, including one or more pins, and a pair of pivot supports for each pin spaced apart in the longitudinal axis of said pin and rotatable about equidistant respectively offset centers.

10 7. In a strip feed mechanism, a pin feed device, including a plurality of pins, a first pivot support for each of said pins, a second pivot support for each of said pins, said second support being spaced from the first support in the longitudinal axis of the pin, a rotatable carrier for said first supports, and a rotatable carrier for said second pivot supports, said carriers being offset a distance corresponding to the spacing between said supports.

15 20 8. In a strip feed mechanism, a pin feed device, including a pair of rotatable discs arranged alongside one another with their axes in parallel offset relation to one another, pivot points on adjacent surfaces of said discs and occupying corresponding positions thereon, and feed pins between said discs and mounted on corresponding pivot points of said discs.

25 9. In a strip feed mechanism, a pin feed device, including a pair of rotatable discs arranged alongside one another with their axes in parallel offset relation to one another, pivot points on adjacent surfaces of said discs and occupying corresponding positions thereon, feed pins between said discs and mounted on corresponding pivot points of said discs, and means for rotating said discs, said pins moving in response to such rotation in continuously upright positions about the axes of said discs.

30 10. In a strip feed mechanism, a strip support, a pin feed device in underlying relation to said support, said device including a pin carrier rotatable about an axis transverse to said support, and pins mounted on said carrier to maintain an approximately perpendicular relation to said support during rotation of said carrier.

35 11. In a strip feed mechanism, a support to receive on one side thereof a perforated strip, a pin feed device on the other side of said support, said device including a pin carrier rotatable about an axis transverse to said support, pins arranged on said carrier successively to engage the perforations in said strip for advancement of the strip, and a mounting for said pins holding said pins perpendicular to the said support during entrance in and withdrawal from the perforations in the strip.

40 12. In an autographic register or like device utilizing marginally punched record forms, a writing table on which the forms are advanced to and from a recording position, form advancement mechanism including pin feed devices and a crank for operation thereof, and a mounting for said mechanism on said writing table.

45 13. In an autographic register or like device utilizing marginally punched record forms, a writing table on which the forms are advanced to and from a recording position, form advancement mechanism carried by said writing table including transversely spaced apart pin feed devices to engage the marginal perforations of the record forms, and means for effecting relative longitudinal adjustment of said pin feed devices with respect to one another for accurate registry with the perforations in the forms.

14. In an autographic register or like device utilizing marginally punched record forms, a writing table on which the forms are advanced to and from a recording position, laterally spaced to longitudinal slots adjacent one end of the writing table, said table supporting transversely spaced apart pin feed devices presenting pins to extend through said slots and engage the marginal perforations in the forms, and a mounting for one of said devices providing for longitudinal adjustment thereof relative to the other device to achieve accurate registry with the perforations in the forms.

15. An autographic register or like device according to claim 14, characterized in that said one device includes a portion forming a part of said writing table, one of said longitudinal slots in the table being formed in said portion.

16. In an autographic register or like device utilizing marginally punched record forms, a writing table on which the forms are advanced to and from a recording position, a form advancement mechanism support secured to said table on the underside thereof, pin feed devices carried by said support adjacent the sides of the table, one of said devices being mounted for lateral adjustment toward and from the other device, crank means for positively operating one of said devices, a drive shaft interconnecting said devices, and an expandable and contractible joint in said shaft for axial elongation and contraction thereof.

17. In an autographic register or like device utilizing marginally punched record forms, a writing table on which the forms are advanced to and from a recording position, said table presenting adjacent one end thereof marginal longitudinal slots, a pin feed device underlying each said slot, each said device including a pair of discs and pins supported therebetween to rise and descend through the slot in a position perpendicular to the table, a gear train to rotate one of said devices, and an interconnecting shaft to transmit the rotation of said one device to the other device.

18. An autographic register according to claim 17, characterized by a common support for said pin feed devices, said gear train and said shaft secured to said writing table on the underside thereof.

19. In an autographic register or like device, a writing table on which the forms are advanced to and from a recording position, form advancement mechanism including form engaging devices and a gear train for driving said devices, a crank for operating said gear train, stud means

on an element of said gear train, a latch engageable with said stud means and releasing member for said latch arranged alongside said crank for substantially concomitant operation therewith.

20. In a strip feed mechanism, a rotatable pin carrier, and a plurality of feeding pins carried by said carrier in approximately continuous parallel relation to one another.

21. In a strip feed mechanism, a rotatable pin carrier, a plurality of feeding pins pivotally connected to said carrier to revolve about the axis of said carrier in response to rotation thereof, and means for maintaining said pins in an approximately continuous parallel relation to one another during rotation of said carrier.

22. In a strip feed mechanism, a rotatable pin carrier, a plurality of feeding pins carried by said carrier to revolve about the axis thereof in response to rotation of said carrier, and means for effecting substantially continuous pivotal adjustment of said pins during rotation of said carrier to maintain said pins in an approximately continuous parallel relation to one another.

23. In a strip feed mechanism, a pin feed device including a rotatable disc, feed pins pivotally mounted on one side of said disc at spaced apart points adjacent the periphery thereof to revolve about the axis of said disc in response to rotation of the disc, and means for maintaining said pins in a position substantially perpendicular to the plane of the strip being fed thereby during rotation of said disc.

24. In a strip feed mechanism, a pin feed device, including a rotatable carrier, feed pins pivotally mounted on said carrier, and a rotatable guide member in offset parallel relation to said carrier and pivotally connected to said pins to maintain the pins in substantially perpendicular relation to the plane of the strip being fed thereby during rotation of said carrier.

ALBERT W. METZNER.
